No. 11,321

August 5, 1879

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONNECTICUT.

DESIGN FOR BRACKETS.

Specification forming part of Design No. **11,321**, dated August 5, 1879; application filed May 10, 1879.
[Term of patent 14 years.]

To all whom it may concern:

Be it known that I, RODOLPHE CHRISTESEN, of the city and county of Hartford, and State of Connecticut, have invented a new and useful Design for a Bracket; and I do hereby declare that the following specification, taken in connection with the accompanying photographic illustration, forming a part of the same, is a full, clear, and exact description thereof.

The novel design hereinafter described relates to ornamental brackets, and consists of the following features: The rectangular portions of the bracket, viz., the top A and back B, both with and without the front curved truss C, are substantially as heretofore. The leaves and stems c , c^1 , and c^2 , branching from or merging with the truss C, and with the rectangular portions of the bracket, contribute somewhat to the general ornamental effect; but they may be omitted or varied in position and form without affecting the principle or characteristic feature of my design, which consists of a central complex figure, which has its base outside of the truss C and its apex projected toward the junction of the top and back of the bracket. This complex figure is composed essentially of two main elements, a curved base, D, and an arch, G. These essential features are supplemented by a central crown-

piece surmounting the arch, and radiating leaves.

The curved base D may be variously ornamented, as, with perforations d and raised semi-triangular figures d' . The arch G may also be ornamented, and its interior may contain open or skeletonized work, as shown.

The central crown-piece e is in the form of a flower, and is united to the bracket at its inner angle by a stem, E. Radiating from the top of the base, below the center of the arch G, are ornamental leaves F, which may be largely varied in form and arrangement, or omitted, without departing from the main feature of the design.

What I claim is—

1. The ornamental design for brackets, embodying near the angle thereof the curved base D and arch G, these parts being connected with the main portion of the bracket, substantially as shown and described.

2. The design for brackets, embodying the base and arch, the crown-piece, and the radiating leaves F, substantially as shown and described.

RODOLPHE CHRISTESEN.
